Primary Examiner—Philip S. Hyder

(21) Appl. No.: 29/141,954

(74) Attorney, Agent, or Firm—Nawrocki, Rooney &
Sivertson, P.A.

(22) Filed: May 16, 2001

(57) CLAIM

The ornamental design for a protective cover for horse blankets, as shown and described.

(51) LOC (7) Cl. 03-01

DESCRIPTION

(52) U.S. Cl. D3/273; D3/301

FIG. 1 is a perspective view of the design invention;
FIG. 2 is a rear elevational view thereof;
FIG. 3 is a front elevational view thereof;
FIG. 4 is a right side elevational view thereof;
FIG. 5 is a left side elevational view thereof;
FIG. 6 is a top plan view thereof; and,
FIG. 7 is a bottom plan view thereof.

(58) Field of Search D3/272, 273, 254,
D3/231, 289, 276, 287, 301; D30/145;
54/79.3, 79.4, 44.1, 44.7; 206/315.1; 190/100
